UNITED STATES PATENT OFFICE.

ROBERT C. MORTON, OF BALTIMORE, MARYLAND.

GRATE-BAR.

1,314,890.

Specification of Letters Patent. Patented Sept. 2, 1919.

Application filed April 4, 1919. Serial No. 287,470.

To all whom it may concern:

Be it known that I, ROBERT C. MORTON, of the city of Baltimore, in the State of Maryland, have invented a certain new and 5 useful Improvement in Grate-Bars, of which improvement the following is a specification.

My invention relates to means for supporting fuel in combustion in locomotive boiler 10 and other fire-boxes or furnaces, and its object is to reduce the extent and expense of foundry construction due to renewals of partially burned grate bars, by a construction in which such damaged bars may, by 15 adjustment, which can be readily and quickly effected, be rendered capable of an extended period of further service.

The improvement claimed is hereinafter fully set forth.

20 In the accompanying drawings: Figure 1 is a plan or top view of a grate bar illustrating an embodiment of my invention; Fig. 2, a side view, in elevation, of the same; Fig. 3, an end view, as seen from the left; Fig. 4, 25 a vertical transverse section, on the line xx of Fig. 2; Fig. 5, a similar section on the line yy of Fig. 1; Fig. 6, a plan view of one end of the cradle member, showing a trunnion thereon; Fig. 7, an end view of the 30 same; Fig. 8, a similar view illustrating a structural modification; Fig. 9, a plan view of one end of the cradle member, illustrating another structural modification; Fig. 10, a side view of the same; Fig. 11, a view, half 35 in end elevation, and half in section, on the line zz of Fig. 10; and, Fig. 12, an end view of one of the bar members of Figs. 9 to 11, inclusive.

In the practice of my invention, referring 40 descriptively to the specific embodiment thereof which is herein exemplified, I provide a carrying member or cradle, indicated, as a whole, by A, and detachable and adjustable fuel supporting bar members, each 45 indicated, as a whole, by B, which are fitted, at their ends, in the carrying member, in such manner as to be readily insertible and removable therein and therefrom, and adjusted to present different fuel supporting 50 surfaces. The cradle comprises two end bar carrying sections, 1, 1, in which are formed draft passages, 1^a, and a cross tie, 1^b, preferably of inverted T section, extending 55 downwardly from, and connecting, the end sections. The cradle may be, as indicated

in the drawings, an integral casting, or, if preferred, the end portions may be made of cast steel, and welded to a wrought iron cross tie.

The cradle may be supported in the furnace in any suitable known manner. Thus, in Figs. 1 to 3, inclusive, and 9 to 11, inclusive, sockets, 1^c, are shown as formed in the end sections, to receive corresponding pins, or trunnions, on bearing bars in the furnace; 60 Figs. 6 and 7, show, as equivalents, trunnions, 1^d, on the end sections, adapted to fit in sockets on bearing bars; and Fig. 8, shows an open bottomed inverted U shaped recess, 1^e, on an end section adapted to fit over a 65 trunnion on a bearing bar, the cradle being held in position thereon by a pin, 1^f, at the bottom of the socket. A rocker arm, 1^g, extends downwardly from one of the end sections of the cradle, or from any other convenient position thereon, and is adapted to be connected to any of the ordinary means for rocking a grate bar manually or by the application of power. 70

The cradle, A, supports, and carries with 75 it, when rocked in its bearings, two counterpart fuel supporting bar members, B, B, which, as most clearly shown in Figs. 4 and 12, are cast metal bars, each comprising two plates, united at a right angle, so as to make 80 the bar of substantially inverted L transverse section, which bar members are fitted detachably in the end sections of the cradle. The connection of the bar members and the cradle is effected by inclined tongues or 85 tenons, 2, on the ends of the bar members, which engage corresponding recesses in the end sections of the cradle, as most clearly shown in Fig. 5. A plurality of transverse air passages, 2^a, is formed in each of the 90 plates of the bars, which are fitted side by side in the cradle, the faces of their upper plates forming the supporting surfaces for the fuel, in the manner of grate bars of the table or box type. It will be obvious that 95 if the draft passages were extended to, and open at, the outer edges of the plates, the latter would be in the form of the ordinary finger grates. 100

The two plates forming each fuel supporting bar member, B, being, as before stated, counterparts, these members may be fitted in the cradle, with either of their plates disposed horizontally to form a fuel support, and, when the then horizontal plate of a 110

bar is burned or damaged to such an extent as to be considered unfit for service, the bar can be detached from the cradle, turned through an angle of ninety degrees, and 5 replaced in the cradle, with the other plate in horizontal position, to form a fuel support. The increase in the service life of the bar by the capacity of thus providing for the substitution of a new and unused fuel 10 supporting surface for one which has become deteriorated or unserviceable, effects a substantial economy, as will be obvious to those familiar with the operation of locomotive boiler fireboxes and other furnaces 15 in which a comparatively high degree of heat is maintained in operation. It will also be seen that the bar members may, when desired, be reversed or turned end for end, in the cradle.

20 Figs. 9 to 12, inclusive, illustrate a modification of structural detail, in which the connection of the bar members to the cradle is effected by means of separated projections, 2^b, disposed in rows at right angles on the 25 ends of the bar members, and adapted to engage vertical passages, 1^h, in the end sections of the cradle. The engagement and disengagement of the bar members and cradle are effected in the same manner as by 30 the means first described.

I claim as my invention and desire to secure by Letters Patent:

1. In an appliance for supporting fuel in furnaces, the combination of a carrying member, and a fuel supporting bar member having a plurality of relatively angularly disposed fuel supporting surfaces and being fitted detachably and adjustably in the carrying member.
- 40 2. In an appliance for supporting fuel in furnaces, the combination of a carrying member; a fuel supporting member having a plurality of relatively angularly disposed fuel supporting surfaces; and means 45 for adjusting said fuel supporting member in the carrying member in position to pre-

sent either of its fuel supporting surfaces at top.

3. In an appliance for supporting fuel in furnaces, the combination of a carrying member, and two counterpart fuel supporting members fitted detachably and adjustably therein, each of said fuel supporting members comprising two plates perforated by air passages and connected at substantially 55 a right angle so that either plate may present a fuel supporting surface at top, as adjusted in the carrying member.

4. In an appliance for supporting fuel in furnaces, the combination of a cradle, 60 comprising two end sections connected by a downward depending cross tie; a bar member comprising two plates perforated by air passages and connected at substantially a right angle; and means for detachably connecting said bar member to the cradle with either of its plates in position to present a fuel supporting surface at top.

5. In an appliance for supporting fuel in furnaces, the combination of a cradle comprising two end sections connected by a 70 downwardly depending cross tie; means for connecting said cradle to a rocking mechanism; a bar member fitted detachably in the cradle between the end sections thereof, and comprising two plates perforated by air passages and connected at substantially a right angle; and correspondingly located tongues or projections on the plates of the bar member, each adapted to engage a passage in the cradle.

6. In an appliance for supporting fuel in furnaces, a fuel supporting bar member comprising in an integral structure, two plates, connected at substantially a right angle, each 85 plate being perforated by a plurality of air passages, and end projections adapted to detachably engage a carrying member.

ROBERT C. MORTON.
